AUSTIN H. REEVES, OF ELMHURST, NEW YORK.

CONCRETE CONSTRUCTION.

Application filed May 4, 1921. Serial No. 466,825.

To all whom it may concern:

Be it known that I, AUSTIN H. REEVES, a citizen of the United States, and a resident of the city of New York, Elmhurst, borough 5 of Queens, in the county of Queens and State of New York, have invented a new and Improved Concrete Construction, of which the following is a full, clear, and exact description.

- 10 This invention relates to concrete structures and has for an object to provide a particular structure which will be very strong and which may be built in successive layers having integral coherency.
- 15 Another object of the invention is to provide a construction for concrete standpipes, tanks, towers and other reservoirs which includes using a series of independent sections of reinforcement.
- 20 A still further object of the invention is to provide a concrete construction in which successive monolithic rings are cast and formed with independent reinforcing members, the same being adapted to be used 25 either with or without anchoring or waterproofing members at the joints and with or without overlapping flanges.

In the accompanying drawing—

- Figure 1 is a side view of one embodiment 30 of the invention, certain parts being broken away for illustrating the detail construction.

Figure 2 is a sectional view through Figure 1 on line 2—2.

- Figure 3 is an enlarged fragmentary sectional view showing the detail arrangement 35 of the concrete and reinforcing members and how they are formed in independent rings.

- Figure 4 is a sectional view similar to 40 Figure 3 but on a somewhat enlarged scale.

In the construction of concrete reservoirs of different kinds, as for instance, standpipes, water towers and the like, it is customary to provide a suitable foundation and 45 then on this foundation erect the container which is usually constructed of concrete having reinforcing rods extending vertically from the foundation up to the top of the structure and suitable annular tie members 50 as well as cross tie members. The vertical reinforcing rods must be straightened out and properly positioned as well as the other reinforcing members before the aggregate can be deposited around the same between 55 the forms. Also, preferably the casting operation is continuous until the entire struc-

ture has been cast so that there will be no weak places or irregular joints. Where a tank or tower is fifty or one hundred feet high, it is very difficult to keep these vertical 60 reinforcing rods in place so as to properly function. It is also very expensive to pour or cast a complete structure at one operation but by the present method it is necessary even though it necessitates working day and 65 night for several days and nights in succession. This day and night work requires the use of several shifts as a rule and sometimes requires an expert to remain on the job for several days and nights in succession without sleep or the employment of two 70 experts.

The method of pouring just mentioned is in vogue at present notwithstanding the fact that it is unscientific in many respects, 75 as for instance, the arrangement of the swaying and projecting tops of vertically positioned reinforcing rods. The swaying of a reinforcing rod while the concrete is still green will push the heavy part of the aggregate away and allow some of the lighter part to move in toward the reinforcement as long as the concrete is in a comparatively liquid state but as soon as it begins to set the continuous swaying of the reinforcement produced by the wind and other causes results 80 in forming an open space around each of the vertical reinforcements for part of its length. When the next batch is placed in position some of this opening is filled in but 85 the connection and the filling is not the same as if the reinforcement had been stationary. According to the present invention, this objection is overcome by the fact that the reinforcement is completely submerged in the 90 wet or green concrete and cannot move.

The present invention aims not only to overcome the unscientific effect involved in the swaying of reinforcing rods but also to decrease to the minimum the very large 100 bending moment produced by the pressure of the contained substance in the shell or wall of tanks, where said shell or wall is a so-called monolithic structure. The large bending moment now common in tanks or 105 other structures as heretofore formed, causes cracks in the walls at unknown or unforeseen points and of unknown extent while by casting the structure in independent rings or sections a well defined line is provided 110 and if any cracks occur they will appear along this line.

As this structure is formed in this manner for large containers, special means may be provided for taking care of this possibility of cracking, as for instance, the positioning 5 of suitable waterproofing contrivances along this line which may take the nature of a filling of asphalt, a sheet of metal or other devices. Therefore, to produce the best results under the old method or rather the 10 method now in common use, it is desirable to pour at one operation a complete container regardless of the size. This is very expensive and sometimes almost impossible. Where very large containers are being constructed, the pouring operation is in successive layers but the vertical reinforcing rods and other reinforcements extend upwardly continuously from the lower portion of the casting so as to bond the parts together. 15 20 After one day's work the concrete is left to set over night or some other desired time and the unused portion of the vertical reinforcements are extending into the air. After the first batch has set the reinforcements are 25 straightened, adjusted and properly positioned for receiving the second batch and so on whereby a construction is produced that is known as a monolithic structure though the different parts have been cast at different 30 times. However, the reinforcing rods extend usually from the top to the bottom of the complete structure.

In the construction shown in the drawing and embodying the invention an arrangement 35 has been provided which provides successive rings or sections of independent reinforcements which are completely submerged at a single point and which will thereby produce an exceptionally strong container scientifically, which container may be a tower tank or other container and which is cast in sections or rings whereby a single shift of workmen may readily and properly cast the complete structure with efficiency. 40 45 The formation of the reinforcements in sections which are completely submerged at a single casting obviates the undesirable swaying of the reinforcing rods now in common use.

Referring to the accompanying drawing by numerals, 1 indicates a foundation of any desired kind, as for instance, a good concrete foundation and 2 the tank or other structure formed thereon. In the drawing 55 the top of the foundation has been illustrated as being near the ground line but it will be evident that the same may be below the ground line or arranged at an appreciable distance above the ground line. In 60 many places where the container is to act as a water tower, suitable columns are provided and the base is positioned on the top of these columns, after which the container itself is poured. In the drawing the container 2 has been illustrated as being cir-

cular but it will be evident that the same may be polygonal or other shape without departing from the spirit of the invention. In forming the construction embodying the invention, as for instance, that shown in the drawing, the base or foundation 1 is first formed and allowed to set, after which, suitable molds or frames are mounted to receive the concrete casting forming the wall 3. In addition, a reinforcing skeleton 4 is provided and properly located between the forms or molds, said skeleton extending for a comparatively short distance upwardly, namely, as far as it is intended to cast one of the rings 5. These rings may be very 70 low or may be ten or fifteen feet high or even more if desired, though ordinarily ten to fifteen feet high would be the limit. The reinforcing structure 4 may be of any suitable kind, as for instance, a number of circumferential rods or wires 6 together with tie members 7 and vertical members 8. The vertical members 8 may be independent rods or may be sections of the tie members 7 as shown at the left in Figure 3. The metallic reinforcement 4 by reason of its short height is usually maintained in proper position and the various bars properly located so that the concrete aggregate may be readily cast with the reinforcement properly located. 80 90 95

In the drawing a certain form of reinforcement and a certain form of joint have been shown but it will be evident that other forms may be readily used without departing from the spirit of the invention. The reinforcement 4 of the lower ring 5 is entirely independent of the reinforcement 4 of any of the other rings. 100

In constructing a container as shown in Figures 1 and 3, the foundation is first provided and allowed to set, suitable reinforcement is then arranged on the foundation and finally the concrete is poured for forming the lower ring 5, which concrete is allowed to set. After the lower ring 5 has been allowed to set, the reinforcement 4 of the second ring is provided and then the aggregate of the second ring is poured into place and allowed to set. The third and succeeding rings, if any, are likewise constructed, each higher ring being cast in place after the next lower ring has set. This arrangement will not only produce the rings as shown but will permit the forms used in holding the aggregate to be gradually moved upwardly to take care of the rings as they are cast. 110 115 120 125

Ordinarily, the lower ring is cast directly on to the foundation with bonding or tying members 10 and likewise the various upper ring or rings are successively cast one on the other with bonding or tying members 9. This construction provides exceptionally strong containers as each of the reinforcing members 4 are intended to take care of the 130

strain of its particular ring so that the strain on one ring will not be unduly communicated to or effect the next adjacent ring.

- 5 This method of dividing up the structure to independently take care of strains is particularly effective where the container is intended for use as a water tank or reservoir. Any suitable structure will readily take care 10 of the weight or pressure of the water, as for instance, an ordinary monolithic structure but where there is an expansion of the water or other matter in the container, monolithic structures will not answer the 15 purpose fully. In fact, where the contents expand by reason of heat or by reason of freezing, cracks are caused and these cracks naturally occur at the weakest points. Where a standpipe is half full of water and 20 the weather becomes very cold, a thick layer of ice will form on the top of the water and, consequently, there will be a tremendous expanding force applied at the central standpipe by reason of the height of the water. 25 This will cause the standpipe to be cracked unless it can yield. If the level of water is near the top, the expansion will either do no injury or will merely crack the top part of the structure.
- 30 In the present construction, these difficulties have been considered and the structure embodying the invention arranged in reinforced rings which are independent but which have a certain coherency. This ring structure reduces the cantilever or bending stresses in the shell and limits the same to one or more rings which may expand somewhat and which will break along the line between the rings in case the pressure or strain becomes too great. This breaking or 35 cracking on a given line permits easy repair.

In some isolated cases it might be desir-

able to bond or connect the rings 5 together and to connect the lower ring 5 with the foundation 1. The bonding bars 9 are set 45 into the lower ring while it is still green, said bars acting to bond the adjacent rings together. Any desired number of bars 10 could also be set into the foundation 1 when the same is green and the first ring 5 cast 50 thereon.

In the drawing a concrete base has been shown as ordinarily this form of base would be used, though other forms of bases, as for instance, a metal base might be used without 55 departing from the spirit of the invention. Also, in the drawing only one tank has been shown but if desired a cluster of tanks or containers may be arranged adjacent each other or formed so as to merge into each 60 other and yet retain the characteristics of the individual arrangement of reinforcing rings.

What I claim is:—

The method of constructing a hollow concrete column comprising the steps of forming a concrete base, inserting in the concrete while green and at various points a plurality of pins with one end projecting above the surfaces of the base, placing on said 65 base a reinforcing member having a plurality of hoops or rings disposed in planes at both sides of said pins, casting concrete around said reinforcing member so that the lower part of said casting fits against said 70 base while wet, allowing said casting to dry, inserting at various points of the casting a plurality of pins with their ends projecting above the upper end of the casting, placing on said casting a reinforcing member similar 75 to the reinforcing member embedded in the casting, and embedding said last-mentioned member in concrete.

AUSTIN H. REEVES.
